Primary Examiner — Robert M Spear*Assistant Examiner* — Ryan Harvey(74) *Attorney, Agent, or Firm* — QuickPatents, LLC;
 Kevin Prince(57) **CLAIM**

I claim the ornamental design for a balance exercise board, as shown and described.

DESCRIPTION

FIG. 1 is a bottom perspective view of a balance exercise board, showing my new design;

FIG. 2 is an exploded bottom perspective view thereof;

FIG. 3 is an exploded front elevational view thereof, the rear elevational view being a mirror image thereof;

FIG. 4 is an exploded left-side elevational view thereof, the right-side elevational view being a mirror image thereof;

FIG. 5 is a top plan view thereof; and,

FIG. 6 is a bottom plan view thereof.
